CLAIM

The ornamental design for a bicycle holder for attachment to a vehicle roof rack, as shown.

DESCRIPTION

FIG. 1 is a top plan view of a bicycle holder for attachment to a vehicle roof rack showing my new design;
FIG. 2 is a front elevation view thereof;
FIG. 3 is a right side elevation view thereof;
FIG. 4 is a bottom plan view thereof;
FIG. 5 is a left side elevation view thereof; and
FIG. 6 is a rear elevation view thereof.

*Fig. 1.**Fig. 5.**Fig. 2.**Fig. 3.**Fig. 4.**Fig. 6.*
